UNITED STATES PATENT OFFICE

2,429,252

CURTAIN ROD OR DRAPERY FIXTURE

Archie A. Allen, Sturgis, Mich., assignor to Kirsch Company, Sturgis, Mich., a corporation of Michigan

Application April 4, 1946, Serial No. 659,582

6 Claims. (Cl. 248—261)

1

This invention relates to improvements in curtain rod or drapery fixtures.

The main objects of this invention are:

First, to provide a curtain rod or drapery fixture of the crane type in which the curtain rod is supported to swing in a generally horizontal plane and which may be easily and quickly adjusted to properly position the rod without disturbing the bracket and while the rod is supported by the bracket.

Second, to provide a drapery fixture having these advantages which is adapted to support curtain rods or drapery rods of widely used types.

Third, to provide a structure having these advantages which is very economical in its parts and can be readily assembled and adjusted by unskilled persons.

Objects relating to details and economies of the invention will appear from the description to follow. The invention is defined and pointed out in the claims.

A preferred embodiment of the invention is illustrated in the accompanying drawing, in which:

Fig. 1 is a fragmentary elevational view partially in section illustrating the fixture in relation to a window casing.

Fig. 2 is an end elevation looking from the left of Fig. 1.

Fig. 3 is a fragmentary view partially in section on a line corresponding to the sectioning of Fig. 1 showing the parts in another adjusted position, the adjusted position being exaggerated to illustrate one limit of adjustment in the structure illustrated.

Fig. 4 is an enlarged fragmentary view in section on the broken line 4—4 of Fig. 1.

Fig. 5 is an enlarged fragmentary view in section on line 5—5 of Fig. 1.

Fig. 6 is a perspective view of the adjusting member of the embodiment illustrated.

In the accompanying drawing, 1 represents a window casing. The embodiment of my invention illustrated comprises a bracket consisting of a base section 2 adapted to be mounted on a window casing or other support. An adjustable section 3 disposed between the flanges 4 of the base section and having a longitudinal slot 5 receives the clamping screw 6 which provides for considerable extension of the bracket in length.

The adjustable section 3 of the bracket is provided with a tubular socket 7, the member 3 being formed of a piece of metal of suitable gauge folded upon itself to provide the socket 7, the ends 8 being brought together to provide the arm portion 55 of the member—see Fig. 5.

The rod supporting member 9 is desirably formed as a die casting or other casting and has a rod receiving arm 10 receiving the tubular rod or crane 11, the rod or crane being commonly 60

2

formed of sheet metal of the desired section. The supporting member 9 rests upon the upper end of the socket, the member 9 in this construction being provided with a second arm 12 adapted as 5 a curtain or drapery anchor or to receive a pull cord or the like.

The socket is provided with stops 13 spaced substantially 180°. The arm 12 constitutes a stop coacting with the stops 13 thereby limiting the 10 swinging movement of the rod or crane.

The rod supporting member 9 is provided with a downwardly tapered shank 14 rotatable and tiltable within the socket as is shown in the drawing. At its lower end, the shank is provided with 15 a side recess 15 adapted to receive or partially receive the adjusting member 16. This adjusting member is of transversely curved section and is disposed at the side of the shank or spindle 14 to bear against the socket wall as is shown in 20 Figs. 1 and 3.

The adjusting member 16 has a laterally disposed ear 17 at its lower end, this ear having a hole 18 therein adapted to receive the screw 19 which is threaded into the lower end of the shank. The ear 17 is disposed at an obtuse angle relative 25 to the adjusting member so that when the screw is tightened or threaded into the shank, the member 16 is tilted outwardly away from the shank. However, it is carried by and rotates with the shank and is, in effect, in bearing supported engagement with the socket.

By adjusting the member 16 the rod or crane is vertically tilted or raised and lowered to the desired position, there being a considerable range 30 of adjustment. This adjustment can be effected without removing the support member from the bracket and when adjusted the rod or crane remains in the same horizontal position relative to the bracket throughout the swing thereof. 35 This is a feature of considerable importance as sometimes it is desired to swing the curtains or drapes away from the window.

Applicant is aware that certain types of swingable cranes have been devised in which the relative position of the rod or crane varies as it is swung from its initial or normal position in front of the window.

I have illustrated and described my invention in a very practical embodiment or adaptation 40 thereof. I have not attempted to illustrate or describe other modifications and adaptations which I contemplate as it is believed that this disclosure will enable those skilled in the art to embody or adapt my invention as may be desired.

Having thus described my invention, what I claim as new and desire to secure by Letters Patent, is:

1. In a curtain or drapery fixture, the combination of a supporting bracket provided with a vertically disposed tubular socket, a rod support-

ing member rotatably supported on said socket and comprising a rod arm and a shank disposed substantially at right angles thereto and rotatable and tilttable within said socket, an adjusting member disposed at the side of the shank for tilting adjustment thereon and in supported bearing relation to the socket, said adjusting member having an angularly disposed ear at its lower end disposed at the end of the shank, and an adjusting screw arranged through said ear and having threaded engagement with the shank whereby the adjusting member may be tiltably adjusted on the shank for vertically raising or lowering the rod arm.

2. In a curtain or drapery fixture, the combination of a supporting bracket provided with a vertically disposed tubular socket, a rod supporting member rotatably mounted on said socket and comprising a rod arm and a shank disposed substantially at right angles thereto and rotatable and tilttable within said socket and having a recess at its lower end opposite the rod arm, a transversely curved adjusting member disposed at the side of the shank for tilting adjustment thereon and in supported bearing relation to the socket and collapsible in said recess thereof, said adjusting member having an angularly disposed ear at its lower end disposed at the end of the shank, and an adjusting screw arranged through said ear and having threaded engagement with the shank whereby the adjusting member may be tiltably adjusted on the shank for vertically raising or lowering the rod arm.

3. In a curtain or drapery fixture, the combination of a supporting bracket provided with a socket, a rod member rotatably supported thereby and having a shank rotatable and tilttable within the socket, an adjusting member disposed at the side of the shank in bearing relation to

the socket and for tilting adjustment on the shank, and means for adjusting said adjusting member.

4. In a curtain or drapery fixture, the combination of a supporting bracket socket, a rod member rotatably supported thereby and having a shank rotatable and tilttable within the socket, and an adjustable member carried by the shank and disposed at the side thereof for rotation with the shank in engagement with the socket, said member having threaded adjusting means.

5. In a curtain or drapery fixture, the combination of a supporting bracket socket, a rod member rotatably supported thereby and having a shank rotatable and tilttable within the socket, and an adjustable member carried by the shank and disposed at the side thereof for rotation with the shank in engagement with the socket.

6. In a curtain or drapery fixture, the combination of a supporting bracket provided with a vertically disposed tubular socket, a rod supporting member comprising a rod arm and a shank rotatable and tilttable within said socket, and an adjusting member disposed at the side of the shank and carried thereby and in bearing relation to the socket, said adjusting member being adjustable from without the socket while the shank is within the socket.
